CARBURETOR

George W. Baker, Chester, Ill.

Application June 17, 1937, Serial No. 148,782

1 Claim. (Cl. 261—51)

This invention aims to provide novel means for breaking up the fuel in a carburetor, and to provide novel means for spraying the broken up fuel, within the air passage of the carburetor, the sprayed fuel being disseminated laterally, instead of being discharged straight down through the air passage, parallel to the axis of the passage, a more complete mixing of the fuel and the air resulting.

10 It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

25 Fig. 1 shows in vertical section, looking in the direction of the arrows in Fig. 2, and on the line 1—1 of Fig. 2, a device constructed in accordance with the invention the butterfly valve being shown in starting or choked position;

30 Fig. 2 is a section on the line 2—2 of Fig. 1; Fig. 3 is a side elevation of the spraying tube; Fig. 4 is a section on the line 4—4 of Fig. 3.

Figs. 5 and 6 are elevations taken at right angles to each other and showing the mechanism for operating the throttle valve, parts being broken away.

The numeral 1 marks the body of a carburetor, having a passage 5 for the mixture of air and fuel. In the passage 5 is located a venturi 2. An accelerating nozzle 3 is mounted in the body 1 and communicates with the venturi 2, near the upper end of the venturi. The means for securing idling adjustment is shown at 4 and need not be further described because it is well known to those skilled in the art.

45 In the lower portion of the passage 5 is located a throttle valve 6 which is carried by a shaft 7 journaled in the body 1. A choke valve 8 is disposed in the upper portion of the passage 5 and is carried by a shaft 9 journaled in the body 1. The float chamber or reservoir for the fuel is designated by the numeral 10 in Fig. 2.

The closure for the float chamber 10 is designated by the numeral 11, and carries a tubular 50 guide 12 wherein an operating member 14, in the

form of a rod, is mounted for vertical reciprocation. The operating member 14 has a reduced upper end 15, defining a shoulder 16 on which one or more washers 17 rest, the end 15 of the operating member passing through the washers. 5 One end 18 of a laterally extended arm 19 is mounted on the end 15 of the rod 14, above the washers 17. A nut 20 is threaded on the reduced upper end 15 of the operating member 14 and binds the end 18 of the arm 19 against the 10 washers 17. The nut 20 may be held against rotation through the instrumentality of a cross pin 21 mounted in the upper end 15 of the operating member 14 and engaged in seats in the nut. The washers 17 may be placed either above or 15 below the end 18 of the arm 19, any desired number of washers may be employed, and the washers may be of various thicknesses, the position of the operating member 14 with respect to the end 18 of the arm 17 being adjusted accordingly. 20

The arm 19 is connected to a vertically movable carrier rod 22, connected by any suitable mechanism 23 to the shaft 7 which carries the throttle valve 6, the construction being such that when the shaft 7 is rocked, the throttle valve 6, 25 25 the carrier rod 22 and the operating member 14 will be moved in consonance.

The operating member 14 is provided in its lower end with a recess 25, receiving a head 26 on the upper end of a control rod 27. The control rod 27 passes through a sleeve 28, threaded into the recess 25 of the operating member 14 and provided at its lower end with a disk-like baffle 29. The upper end of the sleeve 28 engages the lower end of the head 26 of the control rod 27 and, thus, the control rod is secured to the operating member 14. In order to prevent the sleeve 28 from loosening in the operating member 14, a lock nut 30 may be threaded on the sleeve, the lock nut engaging the lower end of the operating member 14. On the lower end of the sleeve 28 there is a transverse baffle disk 29. 35 35

40 The control rod 27 includes an upwardly tapered portion 31 of considerable length, located immediately below the baffle disk 29, the part 31 45 being provided at its lower end with a short downwardly tapered extension 32, merging into a reduced stem 33 connected to an upwardly tapered part 34 having, at its lower end, a depending conical nose 35. The taper of the member 34 is more abrupt than the taper of the member 31. 50

45 A two-part thimble 35 is mounted in the body 1 and communicates with the float chamber 10. The thimble 35 is provided with a chamber 36. 55

there being an inlet 37 at the upper end of the agitating chamber, and an outlet 38 at the lower end thereof. In idling position, the stem 33 extends through the inlet 37, the tapered part 34 of the control rod 27 is located in the agitating chamber 37, and the nose 85 of the control rod is spaced from the outlet 38, all as shown in Fig. 2.

The outlet 38 is in communication with a T-shaped passage 39 in the body 1 of the carburetor. The body 1 has a double-diametered bore 40, which slants upwardly and outwardly with respect to the axis of the control rod 27. Into the bore 40 is threaded a first mixing nozzle 41, provided near its lower end with a transverse bore 42, communicating with the T-shaped passage 39 in the carburetor body. Within the bore 40, the first mixing nozzle 41 is supplied with an external groove 43, defining a space between the first mixing nozzle and the wall of the bore 40. Air finds its way into the groove 43, through a duct 44 in the body 1, the duct communicating with the passages 45 of a plug 46, mounted in the upper portion of the carburetor body.

Should it be necessary to regulate the air supply in idling, recourse is had to a structure shown in Fig. 2, and including a bore 47 in the carburetor, and leading downwardly to the groove 43 of the first mixing nozzle 41. Intermediate its ends, the bore 47 is supplied with a seat 48 engaged by the inner end of a tubular valve 49, threaded into the enlarged upper end of the bore 47 for longitudinal adjustment. The valve 49 has a stem 50 extending downwardly into the bore 47, and the valve 49 has side perforations 51.

The supply of air for idling is regulated by threading the valve 49 up or down, with respect to the seat 48, the air entering the upper end of the valve 49 and passing outwardly through the perforations 51 of the valve. The air passes into the lower portion of the bore 47 and moves into the groove 43 of the nozzle 41 through a reducer 53, mounted in the lower end of the bore 47.

The mixing nozzle 41 has a reduced tip 53, extending into a bore 54 in the carburetor body, the bore communicating with the reduced part 55 of a passage in the carburetor body, the passage including an enlarged portion 56. There is a shoulder 57 in the carburetor, where the parts 56 and 55 of the passage join.

Against the shoulder 57 fits a disk 58 on a second mixing nozzle 59, the nozzle 59 having perforations 60, it being noted at this point that the nozzle 41 of Fig. 2 has similar perforations 61. One end of the nozzle 59 extends into the part 55 of the passage and has a flared inlet 62. The nozzle 59 is received within a casing 63, fitting in the part 56 of the passage and abutting against the disk 58 on the nozzle 59. The casing 63 is enlarged to form a space 64 about the nozzle 59, but the forward end of the nozzle fits closely in the casing, as shown at 65. The casing 63 is provided with openings 66, establishing communication between the space 64 and a circumferential groove 67 formed in the outer surface of the casing 63. Air is admitted into the groove 67 through openings 68 in a plug 69 mounted in the carburetor body. At its inner end, the casing 63 has a flared outlet or mouth 70.

The inner end of the casing 63 is reduced in diameter, so that it may extend within one end 71 of a spraying tube extended across the passage 5, the spraying tube, marked generally by the numeral 72, having a solid end wall 73 located in the carburetor body. Into the carburetor body

is threaded a closure 74, bearing against the end wall 73 on the spraying tube 72. A set screw 75 is threaded into the closure 74 and bears against the end wall 73 of the spraying tube 72. By means of the closure 74 and the set screw 75, the spraying tube 72, the casing 63 and the second mixing tube or nozzle 59 are held securely in place, in a way which will be understood readily from Fig. 1.

The spraying tube 72 has oppositely disposed openings 76, the end edges 77 and 81 of which diverge downwardly and toward the ends of the tube. A disk-like baffle 78 is disposed transversely of the axis of the tube and is located midway between the ends of the openings 76 in the tube. Longitudinal partitions 79 connect the baffle 78 with the upper and lower walls of the tube 72 and form a longitudinal passage 80 in the spraying tube. The partitions 79 terminate in alignment with the edges 81 of the openings 76 in the sides of the spraying tube.

In practical operation, when the shaft 7 is operated, the throttle valve 6 is operated also. By means of the mechanism shown at 23, motion is imparted to the vertically movable carrier rod 22, the rod 22 transmitting movement to the operating member or rod 14, by way of the arm 19. From the operating member 14, vertical movement is transmitted to the control rod 27. In view of the foregoing, it may be stated that the control rod moves in consonance with the throttle valve 6.

In Fig. 2, the control rod 27 is in the position for fast idling. If slower idling is desired, the control rod 27 is moved downwardly until the part 32 of the control rod cooperates more or less with the inlet 37, and until the nose 85 of the control rod cooperates more or less with the outlet 38. In running position, the part 31 of the control rod extends downwardly through the inlet 37, and the part 34 of the control rod extends downwardly through the outlet 38. The fuel, proceeding from the float chamber 10, enters the chamber 36 through the inlet 37. Owing to the fact that the part 34 of the control rod has a more abrupt taper than the part 31, there is no choking or back pressure at the outlet 38 and a thorough breaking up of the fuel in the chamber 36 is brought about, as the fuel moves through the agitating chamber, responsive to piston suction.

From the chamber 36 and the outlet 38, the fuel passes through the T-shaped passage 39, into the bore 42, and from the bore 42, the fuel passes through a reducer 82 in the first nozzle 41, into the nozzle. As the fuel is passing through the nozzle 41, air is drawn through the passages 45 of the plug 46 and through the duct 44, into the groove 43 of the nozzle 41, air entering the nozzle by way of the perforations 61.

The mixture of fuel and air passes out of the tip 53 of the nozzle 41, into the bore 54, and from the bore 54, the fuel passes into the part 55 of the passage in the carburetor body. The mixture enters the second mixing tube or nozzle 59, by way of the flared inlet 62 and moves through the second mixing nozzle. As the mixture moves through the second mixing nozzle 59, a further supply of air is derived through the openings 68 of the plug 69, the external groove 67 in the casing 63, the space 64 between the casing and the nozzle 59, and the perforations 60. Leaving the second mixing nozzle 59, the mixture moves by way of the outlet portion 70 of the casing 63 into the right hand end of the 75

spraying tube 72 in Figs. 1, 3 and 4. In the spraying tube 72, the mixture follows two courses. One of these courses is through the passage 80 that exists between the partitions 79 of the spraying tube. A part of the mixture, therefore, is delivered through the disk-like baffle 78. The air passing through the passage 80, is directed downwardly and laterally by the end edges 77 of the opening 76.

Some of the mixture entering the right hand end of the spraying tube 72 in Fig. 4, follows the arrows A and advances, externally of the partitions 79, rather than through the passage 80. The air moving forwardly outside of the partitions 79 is deflected downwardly by the baffle disk 78, and because the edges 81 of the openings 76 slope downwardly and laterally, there is a lateral dispersion of the mixture. The general construction of the spraying tube 72 is such that the mixture does not tend to shoot downwardly in a straight stream through the air passage 5. The mixture, rather, is spread out laterally and enters the venturi 2 or its equivalent over a wide area substantially coincident in extent with the upper end of the venturi 2.

The general construction of the device is such that the fuel will be thoroughly broken up and a better mixture will be the result.

Attention is directed to the disk-like baffle 29 in the fuel reservoir 10, this baffle serving to prevent air pockets in the gasoline or other fuel, as

the fuel passes downwardly toward the inlet 37.

Having thus described the invention, what is claimed is:

A carburetor having a source of fuel supply and a main passage for the fuel mixture, a spraying tube discharging into the passage, the carburetor having a chamber supplied with an inlet and an outlet, the inlet communicating with said source, the carburetor being provided with a conduit leading from the outlet to the spraying tube, a control member mounted to move through the inlet and the outlet and having means for regulating the effective areas of the inlet and the outlet, mechanism under the control of an operator for actuating the control member, the spraying tube being extended transversely of the main passage and having openings in its sides, the end edges of the openings diverging in the direction of flow through the main passage, the spraying tube being provided with a transverse baffle located intermediate the ends of the openings, and being provided with a longitudinal passage leading through the baffle, the passage communicating with that end of the spraying tube which first receives the fuel mixer, and being laterally open adjacent to said end of the spraying tube, whereby some of the mixture will pass outwardly and engage the baffle, the balance of the mixture moving through the longitudinal passage.

GEORGE W. BAKER.
